(57) **CLAIM**

The ornamental design for a sound bar, as shown and described.

DESCRIPTION

FIG. 1 is a front perspective view of a sound bar, showing our new design;

FIG. 2 is a rear perspective view thereof;

FIG. 3 is a partially enlarged view thereof, taken from FIG. 1;

FIG. 4 is a partially enlarged view thereof taken from FIG. 2;

FIG. 5 is a front view thereof;

FIG. 6 is a rear view thereof;

FIG. 7 is a left side view thereof;

FIG. 8 is a right side view thereof;

FIG. 9 is a top view thereof;

FIG. 10 is a bottom view thereof;

FIG. 11 is a perspective view thereof, shown with the base in a first rotated condition;

FIG. 12 is a rear perspective view thereof, shown with the base in a first rotated condition;

FIG. 13 is a partially enlarged view thereof, taken from FIG. 12;

FIG. 14 is a front perspective view thereof, shown with the base in a second rotated condition;

FIG. 15 is a rear perspective view thereof, shown with the base in a second rotated condition; and,

FIG. 16 is a partially enlarged view thereof, taken from FIG. 14.

The broken lines in the figures show portions of the sound bar that form no part of the claimed design.

The dot-dot-dash broken lines of FIGS. 1-4, 12-14, and 16 are included to show partially enlarged views only and form no part of the claimed design.
